UNITED STATES PATENT OFFICE.

FREDRICK M. WRIGHT, OF FERN RIDGE, MISSOURI.

CAR-COUPING.

SPECIFICATION forming part of Letters Patent No. 293,995, dated February 19, 1884.

Application filed November 16, 1883. (No model.)

To all whom it may concern:

Be it known that I, FREDRICK M. WRIGHT, a citizen of the United States, residing at Fern Ridge, in the county of St. Louis and State of Missouri, have invented certain new and useful Improvements in Car-Couplings, of which the following is a specification, reference being had therein to the accompanying drawings.

10 This invention relates to car-couplings; and it consists in certain improvements in the construction of the same, as herein described and claimed.

15 In the accompanying drawings, Figure 1 is a side elevation of a draw-head and coupling having my improvements. Fig. 2 is a bottom plan of the same. Fig. 3 is a front view of same. Fig. 4 is a longitudinal central section of draw-head, &c.

20 A designates the draw-head, resting loosely within suitable frame-work on a cross-bar, B, and having therein a coupling-hook, C. The hook is beveled or rounded in front, to be readily lifted by the coupling-link coming in

25 contact with it, and is formed with a projection or shoulder, c, near its rear end, against which the link strikes, thus closing the hook. Within the draw-head is a raised surface, a, with a groove, b, in which the hook rests when

30 coupled, the raised surface holding the link a' somewhat higher than the point of the hook when the latter is closed. The draw-head has a slot, d, in the top, to allow the hook to be raised, an aperture, e, for inserting a coupling-pin in case the hook should be broken, and a flange, e', on the bottom to bear against the cross-bar B in draft. The hook is pressed downward by a spring, f, and is secured by a bolt, f', passing through a tubular formation,

40 x, in the casing of the draw-head, so that it is protected from contact with the link. The rear end of the draw-head has a pivotal connection at D with a sliding draw-bar, E, which passes rearward through an aperture in one

45 end of a box, F, firmly fastened to the car. To the rear end of the draw-bar E is fastened a plate, G, which moves on the fixed guide-rods g, which extend through the box lengthwise and pass through apertures in the plate.

50 Four spiral springs, h, are placed on the guide-rods g, two of said springs being forward and

two rearward of plate G, and all of said springs bearing against said plate, and also against the casing of box F, as shown. The said plate G has two arms, k, extending in opposite directions through the slots i in the sides of box F, said arms being connected with the buffing apparatus, as hereinafter stated.

Within the box F, and fixed at the rear end thereof, is an elastic buffer, H, the same being 60 in line with the sliding draw-bar E, for the purpose of concussion with it. The box has a removable sliding lid, I, which forms the bottom, and is kept closed by any suitable device. The guide-rods g, being passed through 65 the box and through a cross-beam, J, of the car, and being secured at their extremities, serve to hold the box securely in place. The said box is further secured by a band, l, passing about it and setting against flanges m on 70 the box, the ends of the band being made fast to the bottom of the car. The draw-bar E has an enlargement at its rear end, forming shoulders n, which bear against the front casing of the box during draft.

75 Two pivoted levers, K, are each connected at one end with an arm, k, of the plate G, the outer end of each of said levers being connected with a rod or bar, L, which passes through one of two fixed wooden buffers, M, at 80 the end of the car, between which the draw-head is located. Each of the rods L has a cap or buffing plate, p, at its forward extremity, for the purpose of contact when the said rods are pushed forward. From this construction it 85 will be seen that as the draw-head is pushed backward in the operation of coupling, the plate G is also moved backward, and, through the pivoted levers, moves forward the rods L with buffing-plates p, which are thus pushed 90 in contact with opposite buffers, and thus protect the draw-head.

A shaft, N, is placed across the end of the car, having suitable bearings, O, and connected centrally by chains r with the draw-head A. 95 The ends of said shaft are squared, to receive a handle, q, used for rotating the shaft when it is desired to raise the draw-head somewhat in coupling, this being usually done by some one standing on the ground at either side of the car. 100 Another shaft or roller, P, is placed across the end of the car, said shaft being properly sup-

ported above the platform, and connected centrally by a chain, *s*, with the coupling-hook for the purpose of raising it. The said shaft has at each end a handle, *t*, so that it may be 5 rotated and the coupling-hook raised by a person standing at either side of the car. Each handle *t* is made, as shown, somewhat in the form of the letter **S**, and so constructed that when it is turned around, one end, *w*, of the 10 handle, which is somewhat flat at the extremity, binds against the platform of the car enough to retain the shaft or roller *P* in position, the coupling-hook being sufficiently raised. The link then entering the draw-head 15 strikes the shoulder or projection *c*, when the hook is immediately closed and the coupling is effected.

To enable a person standing on the top of the car to raise the coupling-hook, a pulley, *Q*, 20 provided with a hand-lever, *u*, is placed on the top, said pulley being connected with the coupling-hook by a chain, *v*.

I claim—

1. In a car-coupling, a draw-head connected 25 with a draw-bar, *E*, with moving plate *G*, secured thereto, and connected with pivoted levers *K*, and the rods *L*, provided with buffering-plates *p*, the parts being properly supported, substantially as and for the purposes described.
2. In combination with a draw-head having 30 a draw-bar, *E*, coupled thereto, a box, *F*, plate *G*, moving on guide-rods *g* within the box, piv-

oted levers *K*, connected with plate *G*, rods *L*, provided with plates *p*, and the buffers *M*, the parts being properly secured in position, substantially as and for the purposes set forth. 35

3. In combination with a draw-head and draw-bar loosely supported, as shown, the moving plate *G*, having arms *k*, connected with levers *K*, which are connected with buffering-rods 40 *L*, the slotted box *F*, provided with a removable bottom, the guide-rods *g*, and springs *h*, the parts being constructed substantially as shown, for the purposes set forth.

4. In combination with a draw-head having 45 a coupling-hook, a roller, *P*, journaled in bearings secured to the car and connected by chain with the hook, said roller being provided with the fixed handles *t*, each having one arm longer than the other, and constructed to bind against 50 the car, as herein set forth, for the purpose specified.

5. In combination with draw-head loosely supported, as shown, a rotative shaft, *N*, having bearings fixed to the car, said shaft being 55 connected by chains with the draw-head and provided with the removable handles *q*, substantially as set forth and described.

In testimony whereof I have affixed my signature in presence of two witnesses.

FREDRICK M. WRIGHT.
